Application filed January 31, 1896. Serial No. 577,630. Term of patent 3½ years.

To all whom it may concern:

Be it known that I, ARTHUR MIDDLETON ROSE, a citizen of the United States, and a resident of Yonkers, in the county of Westchester and State of New York, have invented 5 a new and original Design for Carpets, of which the following is a specification.

My design is intended to be used as a border for carpets; and I do hereby declare that 10 the drawing accompanying this specification conveys to any one a clear understanding of the same and is sufficient to enable such person to use my invention.

The design is characterized by a central

table form surrounded with diverging spirals, 15 leaves and flowers and having connecting-festoons of flowers and leaves.

What I claim as new, and desire to secure by Letters Patent, is—

The design for carpet, substantially as 20 shown.

In testimony whereof I have signed my name to this specification in the presence of two subscribing witnesses.
